[57] CLAIM

The ornamental design for a combined finger-mounted portable lamp and wrist-mounted power pack therefor, as shown and described.

DESCRIPTION

FIG. 1 is a front perspective view of the combined finger-mounted portable lamp and wrist-mounted power pack therefor showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is an end elevational view thereof as seen from the right of FIG. 1;

FIG. 7 is an end elevational view thereof as seen from the left of FIG. 1.

The electric cord between the lamp and power pack is fragmentarily shown for convenience of illustration.
